DESIGN FOR A COMBINED TIE CLASP AND PENCIL

David Turet and Bernard Roberts, New York, N. Y.

Application June 1, 1940, Serial No. 92,748

Term of patent 7 years

To all whom it may concern:

Be it known that we, David Turet and Bernard Roberts, citizens of the United States and residents of New York city, have invented a new, original, and ornamental Design for a Combined Tie Clasp and Pencil, of which the following is a specification, reference being had to the accompanying drawing, forming part thereof.

In the drawing:

Fig. 1 is a side view of a combined tie clasp and pencil showing our new design.

Fig. 2 is at plan view thereof.

Figs. 3 and 4 are opposite end views of the same.

We claim:

The ornamental design for a combined tie clasp and pencil, substantially as shown.

DAVID TURET.
BERNARD ROBERTS.
